R. L. BRINKLEY.

FIRE ALARM.

APPLICATION FILED JAN. 11, 1915.

1,154,480.

Patented Sept. 21, 1915.

UNITED STATES PATENT OFFICE.

ROBERT L. BRINKLEY, OF WINSTON-SALEM, NORTH CAROLINA.

FIRE-ALARM.

1,154,480.

Specification of Letters Patent. Patented Sept. 21, 1915.

Application filed January 11, 1915. Serial No. 1,631.

To all whom it may concern:

Be it known that I, ROBERT L. BRINKLEY, a citizen of the United States, residing at Winston-Salem, in the county of Forsyth and State of North Carolina, have invented certain new and useful Improvements in Fire Alarms; and I do declare the following to be a full, clear, and exact description of the invention, such as will enable others skilled in the art to which it appertains to make and use the same.

My invention relates to improvements in fire alarms and has for its object to provide a very simple and efficient combination of parts including a telephone having a circuit closing member, a normally idle graphophone having a member to be actuated to set it in motion, the graphophone being adapted to announce to the telephone the location of the fire, electro-magnetic means for operating the circuit closing member of the telephone and the operating member of the graphophone, and a fire operated circuit closer for energizing said means. In applying such a combination of parts to practical use in the most simple and efficient manner, I employ the numerous novel features of construction and combination hereinafter described and claimed and shown in the drawing in which a diagrammatic side elevation of the device is illustrated.

In this drawing, constituting a part of the application, the numeral 1 designates a base which may well be the top of a desk or table and upon which a graphophone 2 and a telephone 3 are mounted.

The graphophone 2 may be of any preferred type and is here shown as including a crank 4 for winding its spring, a member 5 for releasing said spring, a record 6 adapted to be driven by said spring when released, a transmitter 7 having a needle contacting with the record, and a transmitting horn 8 which leads outwardly from said transmitter. This horn 8 is disposed in horizontal alinement and is spaced only a slight distance from a receiving horn 9 with which the telephone transmitter 10 is equipped.

In addition to the horn 9 and transmitter 10, the telephone 3 is provided with an arm 11 which on the ordinary telephone, is held normally in lowered position by the weight of the receiver to break the circuit of the telephone, which circuit is completed when the arm is allowed to rise. In the present

case, however, no such receiver is provided, but this arm may be held in lowered position by any appropriate means not shown, since mechanism is employed for forcing it upwardly to active position.

Interposed between the telephone 3 and the graphophone 2 and resting upon the base 1, is a second base 15 from which a pair of standards 16 and 16' rise, these standards being located respectively contiguous to the graphophone and telephone, as clearly shown.

Fulcrumed between its ends at 17 upon the upper end of the standard 16, is a substantially horizontal lever 18 which is provided with an upturned power arm, the lever therefore becoming in effect, a bell crank, the upright arm of which is connected by a link 19 to the member 5 in such a manner as to dispose this member 5 to active position to start the graphophone, when the horizontal arm of the lever 18 is depressed.

Adapted to be depressed simultaneously with the depression of the lever 18, is a second lever 20 which is fulcrumed between its ends to the upper end of the standard 16', one end of this lever 20 being connected by a link 21 to the arm 11 whereby depression of its other end will raise said arm to active position, thus completing the circuit of the telephone.

For the purpose of simultaneously depressing the free ends of the levers 18 and 20, a pair of electro-magnets 25 are mounted upon the base directly beneath these ends, one terminal of these magnets being connected by a wire 26 to one terminal of a battery 27, the opposite terminal of which is connected by a second wire 28 to one terminal 29 of a heat operated circuit closer 30. The other terminal 31 of this circuit closer is in turn connected by a wire 32 to the remaining terminal of the magnets 25. By this construction, it will be seen that the moment the circuit closer 30 is disposed to active position to complete the circuit, the electro-magnets 25 will move the free ends of the levers 18 and 20 downwardly, thus simultaneously starting the graphophone and completing the circuit of the telephone, the graphophone being adapted to transmit to the telephone, the fact that fire prevails at a certain point in the building in which the device is installed, and to give the exact location of such fire. This informa-

tion received by the telephone, will be transmitted from the wires leading therefrom to the central telephone station, whereupon the operator of such station will convey the information received to fire headquarters. By this cycle of operation, the various fire companies can quickly and accurately locate the point at which the fire prevails without first locating the box commonly used for 10 sounding such fire alarms.

It may here be explained, that the information to be communicated to the central telephone office, may be duplicated a number of times on the record 6, thereby insuring 15 that such station will receive the proper information.

Above, I have particularly described a circuit closer 30, which device may be in the form illustrated in the drawings or may be 20 of any appropriate type. In the present embodiment, however, this element is shown as comprising a plate 35 which may well be attached to the ceiling of a room or to another appropriate support, a pair of rigid posts 25 36 and 36' which depend from the opposite ends of said plate, a third rigid post 37 depending from the intermediate portion of said plate, and carrying the terminal 29, and a pivoted post 37', this last named post 30 being equipped with a contact point adapted to be brought into contact with a similar point on the post 37, by a spring 38 when a highly combustible connector 39 is severed by fire. By reference to the drawing, it will 35 be seen that one end of the spring 38 is connected to the post 36 while its other end is connected to the free end of the pivoted post 37' whereas the opposite ends of the combustible member 39 are connected respectively with such post 37' and with the other post 36'.

As herein before stated, practically any appropriate form of circuit closer could be employed in connection with the system de- 45 scribed, but since the specific form just described is very simple in construction and yet is very efficient, I prefer to use the same.

I have described and illustrated but one 50 unit of the system since this is ample to convey the novel features of the device, but it is to be understood that such units may be duplicated at the necessary points, and in fact, a number of circuit closers 30 could well be positioned at different parts of a building and could be so connected with the electro-magnets 25 as to energize the same, when any particular one of such closers is operated.

From the foregoing description, taken in 60 connection with the accompanying drawings, it will be seen that a very simple and efficient fire alarm system has been pro-

vided for carrying out the object of the invention, and that the graphophone and telephone may be of ordinary construction, 65 whereas the other salient features of the mechanism may be inexpensively manufactured and may easily be applied to use.

I claim:

1. A fire alarm comprising a telephone 70 and a normally idle graphophone, the graphophone being adapted to announce to the telephone, the location of the fire when set in motion, an operating member to be actuated to set the graphophone in motion, and 75 a circuit closing member to close the circuit of the telephone, in combination with a base disposed between the telephone and the graphophone, a pair of spaced standards rising from said base, a pair of substantially 80 horizontal levers fulcrumed to said standards, a connection between one lever and the operating member of the graphophone, a second connection between the other lever and the circuit closing member of the telephone, electro-magnetic means on the base 85 below the levers and adapted to operate the same when energized, an electric circuit including said electro-magnetic means and a source of current, and a fire operated circuit closer likewise included in said circuit. 90

2. A device designed to be used in connection with a telephone and a graphophone, the graphophone being arranged with its transmitting horn in alignment with the receiving horn of the telephone, whereby the graphophone is adapted to announce a message to the telephone when set in motion, comprising a base, a pair of spaced standards rising from said base, a horizontal lever 100 fulcrumed intermediately of its ends to one of said standards, a link pivotally connected to the outer end of said lever and adapted at its other end for pivotal connection with the circuit controlling arm of said telephone, 105 a lever fulcrumed intermediately of its ends to the other standard, the inner end of said lever being substantially horizontal and the outer end being bent upwardly whereby to form substantially a bell crank lever, a link 110 pivotally connected at one end to the outer end of said bell crank lever, means for connecting the other end of the link to the starting member of the graphophone, and electro- 115 magnets secured to said base, one being arranged beneath the inner ends of each of said levers.

In testimony whereof I have hereunto set my hand in presence of two subscribing witnesses.

ROBERT L. BRINKLEY.
